(57) **CLAIM**

The ornamental design for a swaddle blanket, as shown and described.

DESCRIPTION

FIG. 1 is a top perspective view of a swaddle blanket showing our new design in a preparatory stage of wrapping the swaddle blanket around an infant;

FIG. 2 is a top perspective view thereof showing the swaddle blanket wrapped around the infant;

FIG. 3 is a right side elevation thereof;

FIG. 4 is a rear plan view thereof; and,

FIG. 5 is a left side elevation thereof.

The broken lines in the drawing views are included to illustrate environment only and form no part of the claimed design.
